Primary Examiner — Derrick Holland*Assistant Examiner* — Jennifer O King(74) *Attorney, Agent, or Firm* — Faegre Baker Daniels LLP(57) **CLAIM**

The ornamental design for a cable splitter housing, as shown and described.

DESCRIPTION

FIG. 1 is a first side view of a cable splitter housing;

FIG. 2 is a top plan view thereof;

FIG. 3 is a second side view thereof;

FIG. 4 is an end view thereof; and,

FIG. 5 is a perspective view thereof.

The broken lines shown represent unclaimed subject matter and form no part of the claimed design.
